UNITED STATES PATENT OFFICE.

RICHARD TAYLOR WALLACE, OF GAINESVILLE, FLORIDA.

DESIGN FOR A GAME-BOARD.

SPECIFICATION forming part of Design No. 31,263, dated July 18, 1899.

Application filed June 13, 1899. Serial No. 720,416. Term of patent 7 years.

To all whom it may concern.

Be it known that I, RICHARD TAYLOR WALLACE, a citizen of the United States, residing at Gainesville, in the county of Alachua and State of Florida, have invented and produced a new and original Design for Game-Boards, of which the following is a specification, reference being had to the accompanying drawings, forming part thereof, in which—

Figure 1 is a plan view of my newly-designed game-board, and Fig. 2 a cross-section on the line 2 2 of Fig. 1.

As shown in the drawings, the leading or material feature of my design consists of a board 5, provided with a central rectangular figure 6 and radial extensions 7 at each corner thereof, which extend to the corner of the board 5, and at the outer ends of each of which is an irregular figure 8, in each of which are placed four holes or openings 9, which are arranged in the form of a rectangle, and corresponding holes or openings 10 are arranged in a longitudinal line in the radial corner extensions 7 of the central figure 6.

The central rectangular figure 6 is formed by parallel side lines 11, between which are placed holes or openings 12, similar to the holes or openings 10, and within said central rectangular figure 6 is another rectangular figure 13.

Connected centrally of each side with the separate sides of the central rectangular figure 6 are radial spaces 15, formed by parallel lines and in which are formed holes or open-

ings 16, similar to the holes or openings 10 and 12, and the interior rectangular figure 13 is also filled with corresponding holes or openings 17, which are arranged in lines which cross each other at right angles and in each of which four of said holes or openings are formed.

The central rectangular figure 6, the interior and rectangular figure 13, and the corner extensions 7 of the central rectangular figure 6, together with the irregular figures 8 at the corners of the board, are all formed by parallel lines, and at each of the corners of the rectangular central figure 6 are transverse oblong figures 18, the ends of which are pointed, and oblong rectangular figures 19 are formed adjacent to the sides of the central figure 6 and connected therewith by parallel lines 20, and the corner spaces of the central rectangular figure 6 are divided by diagonal parallel lines 21.

Having fully described my invention, I claim as new and desire to secure by Letters Patent—

The design for a game-board herein shown and described.

In testimony that I claim the foregoing as my invention I have signed my name, in presence of the subscribing witnesses, this 9th day of June, 1899.

RICHARD TAYLOR WALLACE.
